CRUCIBLE FURNACE

Chester E. Milligan, Cincinnati, Ohio, assignor to
 Electro Refractories & Alloys Corporation,
 Lackawanna, N. Y.

Application October 11, 1941, Serial No. 414,549

6 Claims. (Cl. 263—11)

This invention relates to improvements in crucible furnaces for use mainly in connection with the melting and refining of metals.

When crucible furnaces are used in connection with the melting of certain materials or ingredients, it is necessary to keep outside air as much as possible from contact with the contents of the crucible in order to prevent excess oxidation of the contents. Attempts have heretofore been made to accomplish this result by various means. For example, in one type of crucible furnace, a cover is provided for the furnace which closes the top of the crucible, the products of combustion being discharged from the sides of the furnace. Another type of crucible furnace has a cover with a small vent hole therein over the crucible, the cover being spaced vertically from the crucible, to permit products of combustion to pass over the edges of the crucible and to the vent hole. Both of these constructions are objectionable in that the covers must be removed when the crucible is charged or when ingredients are added, and when the molten material must be removed from the crucible.

One of the objects of this invention is to provide a crucible furnace of improved construction, in which the interior of the crucible is readily accessible at all times without removing the lid or cover of the furnace, and in which a curtain of combustion gases is formed over the top of the crucible.

It is also an object of this invention to provide a crucible furnace of such construction that substantially the entire top of the crucible is open for charging and discharging, and in which the gases of combustion are so directed over the top of the furnace as to produce improved heat distribution and better thermal efficiency.

Another object of this invention is to provide a crucible furnace of improved construction in which the top or cover has an opening therein which is amply large enough to afford access to the interior of the crucible for feeding material thereto or for discharging the molten material therefrom, and in which means are provided for directing the products of combustion over the upper surface of the molten material in the crucible in such a manner as to substantially exclude air from contact with the contents of the crucible.

A further object of this invention is to provide a crucible furnace in which the passages for products of combustion over the top of the crucible is such as to avoid flow of gases of combustion downwardly toward the material in the

furnace and also to prevent whirling of the gases passing over the crucible, so that no rotary or whirling motion is imparted to the contents of the crucible.

5 It is also an object of this invention to provide a crucible of improved construction which is so formed as to cooperate with a furnace so as to produce a curtain of products of combustion across the top thereof.

10 Other objects and advantages of this invention will be apparent from the following description and claims.

In the accompanying drawings, which show by way of example several embodiments of this invention:

15 Fig. 1 is a vertical central sectional elevation of a crucible furnace embodying this invention.

Fig. 2 is a sectional plan view thereof, on line 2—2, Fig. 1.

20 Figs. 3 and 4 are fragmentary central sectional elevations of the upper portions of the crucible furnaces of two modified constructions.

Fig. 5 is a bottom plan view, on a reduced scale, of the top or cover member of the furnace shown 25 in Fig. 4.

Fig. 6 is a top plan view of the crucible shown in Fig. 3, removed from the furnace.

Fig. 7 is a fragmentary sectional elevation, on line 7—7, Fig. 3.

30 Fig. 8 is a top plan view of a crucible of modified construction.

35 My invention may be applied to any suitable or desired type of crucible furnace, and in the accompanying drawings, the furnace is shown as of substantially cylindrical shape, having an outer cylindrical wall 10 and a bottom wall 11, both of which may be of metal. 12 represents a layer of insulating material arranged within the cylindrical outer wall 10 of the furnace, and

40 a layer of fire brick or other suitable refractory material 14 is arranged above the bottom wall 11 of the furnace to protect the same against the heat in the interior of the furnace. If desired, the outer and bottom metal walls may be omitted. The side walls of the furnace may be lined with any suitable refractory composition.

45 15 represents the crucible which may be made of any suitable or desired shape and material, and this crucible preferably rests upon a suitable pedestal block or base 18 supported by the bottom of the furnace and preferably made 50 of a suitable refractory material.

55 The interior of the furnace is preferably cylindrical and the crucible and the pedestal 18 are preferably of circular cross section and of mate-

rially smaller diameter than the inner diameter of the furnace, so as to form an annular space or combustion chamber in which flame and products of combustion may travel about the crucible. The fuel and flame by means of which the furnace is fired may be admitted to the annular combustion chamber between the crucible and inner wall of the furnace in any suitable or desired manner, and in the construction shown, the side wall of the furnace is provided with an opening or burner hole 20 through which a fluid fuel burner may extend into the furnace, preferably in a substantially tangential direction. The furnace may also be provided in the lower portion thereof with a slag hole 21. A furnace of any other suitable or desired construction may be employed.

The furnace also includes a top wall or cover which is preferably of annular shape and which rests on top of the furnace wall. This top or cover may be of any suitable or desired form, and in the construction shown, includes an iron ring 24 and a ring 25, Figs. 1 and 2, of refractory material which is bonded or otherwise suitably secured to the lower face of the reinforcing ring 24, and which protects the ring 24 against damage from the flame or products of combustion. The ring 24 may, however, be omitted, if desired. The cover may be held in place on the furnace in any suitable or desired manner, and may merely rest by gravity on the top wall of the furnace. In the particular construction shown, the top metal ring 24 of the cover is provided at intervals with outwardly extending arms or brackets 27. Clamping bolts 28 connect the arm of brackets 27 of the cover with brackets 29 arranged on the side wall of the furnace to securely hold the cover in place on the furnace. It will be noted that the cover or lid of the furnace is provided with a central hole or opening 30 which is approximately of the same diameter as the top of the interior of the crucible 17.

In accordance with this invention, means are provided for protecting the contents of the crucible from damage or excessive oxidation, without rendering the contents of the crucible less accessible, and this is accomplished by providing means for directing the flame and products of combustion from the combustion space of the furnace laterally across the top of the crucible in such a manner that the air will be excluded from the crucible to the maximum extent. It is also desirable to provide means for conducting the flame and products of combustion across the top of the crucible in such a manner that this flame and products of combustion will not be directed downwardly toward the contents of the crucible, since any heavier or solid particles of matter contained in the products of combustion would then be discharged into the crucible and contaminate the material therein. It is also very important that the products of combustion and flame be directed crosswise of the crucible in such a manner as to avoid imparting any rotary motion to the molten contents of the crucible since such rotary motion of the crucible contents is very damaging to the crucible wall.

In order to accomplish these results, I have provided in the upper portion of the furnace, one or more arc-shaped discharge passages through which flame and products of combustion may pass from the combustion chamber. These passages extend horizontally between the lid or cover of the furnace and the upper edge of the

crucible. These passages may either be formed by notching out one or more portions of the top of the crucible or by providing corresponding grooves or recesses in the lower face of the cover or lid of the furnace or notching or recessing both the crucible and the furnace top or cover.

In the particular construction shown in Figs. 1 and 2, the passages for the products of combustion are formed both by means of notches or recesses in the upper edge of the crucible and by grooves in the cover. In these figures, I provide in the under or lower face of the cover or furnace top a plurality of grooves or recesses 32 extending outwardly from the central hole or aperture 30 and terminating at their outer ends at or near the inner wall of the furnace. The outer portions of the grooves or recesses are preferably inclined or beveled, as shown at 33, to assist in guiding or deflecting the products of combustion so that the same flow radially and substantially horizontally from the combustion chamber over the upper portion of the crucible. The grooves 32 in the cover are formed so as to be in registration with notches or depressions 35 in the upper edge of the crucible, so that the notches 35 together with the grooves 32 form the passages for the products of combustion. If desired, the notch or notches in the crucible may be arranged out of registration with the groove or grooves in the cover. Between the grooves 32, the lower face of the cover is flat and in contact with or in close proximity to the unnotched portions 36 of the crucible. In the particular construction shown, three grooves and cooperating notches are employed, which are unevenly spaced about the axis of the furnace, but any desired number of notches and grooves may be employed and they may be arranged in any desired manner about the periphery of the crucible.

In the operation of the furnace described, assuming that the burner extending through the hole 20 discharges fuel and flame substantially tangentially into the combustion space between the inner wall of the furnace and the crucible, this flame will heat the wall of the crucible 17 and will rise to the upper portion of the combustion space, whereupon it will pass through the passages formed by the notches 35 and the grooves 32 of the cover or lid and will, consequently, pass in a substantially radial and horizontal direction across the upper part of the crucible. The flame and/or hot products of combustion in passing over the material in the crucible will impart a portion of their heat by radiation to the material in the crucible and at the same time, the flame and gases will form a curtain over the top of the crucible, which will to a large extent exclude air from the crucible, and thus prevent excessive oxidation of the material in the crucible. By means of the arrangement described, it will be noted that the flow of products of combustion across the crucible is substantially horizontal and finally upwardly, so that there is no tendency of the flame or combustion gases to flow downwardly toward the contents of the crucible, which downward flow would result in the throwing out of solid or liquid particles from the products of combustion into the crucible. The construction described also has the advantage that because of the large size of the hole or opening 30 in the cover of the furnace, the flame or combustion gases will flow upwardly slowly, thus making it possible for them to transmit a greater portion of the heat con-

tained therein to the contents of the crucible than would be possible if they were forced to flow more rapidly through a smaller hole or opening. Consequently, the large hole 30 not only facilitates the charging and discharging of the crucible but also increases the thermal efficiency of the furnace.

In Figs. 3, 6 and 7, the furnace is provided with a top or cover 40 which may be similar in construction and shape to that shown in Figs. 1 and 2, except that the lower surface thereof is substantially flat, the grooves or recesses shown in Figs. 1 and 2 being omitted. In this furnace, a crucible 42 is employed having one or more notches or depressions 43 in the upper edge thereof, of sufficient size to carry the products of combustion from the combustion chamber across the top of the crucible.

In some cases, it may be desirable to employ a crucible without the notches in the upper edge thereof, so that the full capacity of the crucible may be utilized. In such case, a construction may be employed as shown in Figs. 4 and 5, in which the cover 50 is provided with one or more grooves or recesses 51 formed on the lower surface thereof, and in this construction, the crucible 52 is provided with an unnotched or plain upper edge. The groove or grooves 51 in the cover provide for the passage of the products of combustion across the top of the crucible 52.

In the construction shown in Figs. 3 to 7, no particular precaution need be employed in placing the cover or top of the furnace into its operative position, whereas in Figs. 1 and 2, it may be desirable that the grooves in the cover be substantially in registration with or in definite relation to the notches in the crucible.

In the various constructions shown in Figs. 1 to 7 inclusive, the notches in the crucible or the grooves in the cover are irregularly spaced from each other, leaving a relatively large unnotched or ungrooved portion at one side of the furnace. This arrangement will tend to cause the gases of combustion to flow upwardly somewhat more adjacent to the larger unnotched or ungrooved portion of the furnace, so that while the furnace is in operation, an operator may without difficulty approach the furnace for charging or discharging the same while the burner is in operation, if he approaches the furnace at portions thereof remote from the unnotched or ungrooved part of the largest dimension. It is, however, not necessary that the furnace be so constructed, since any suitable arrangement of grooves or notches about the periphery of the crucible may be employed. By way of example, there is shown in Fig. 8, a crucible 60 of a different form having a relatively large number of notches 61 in the upper edge thereof, which are spaced between a similar number of parts 62 which extend upwardly into close proximity to the cover.

The passages for products of combustion formed by notches in the crucible and/or grooves in the cover may vary in size or cross sectional area, depending upon the amount and type of fuel which is being used per unit of time. For example, if a furnace is operated on a very short cycle, larger openings will be required to accommodate the relatively large volume of combustion gases, than when a furnace is operated on a relatively long cycle, or in other words, is heated more gradually.

While the flame and products of combustion within the combustion chamber generally travel in a substantially helical or circular path, yet

the direction of movement of the gases of combustion when they pass through the passages formed by the grooves or notches is modified so that the gases are discharged through these passages between the cover of the furnace and the crucible in a direction substantially toward the axis of the same. Consequently, the gases forming a curtain over the top of the crucible have very little circular or rotary motion and do not impart such motion to the contents of the crucible. This is important since agitation or a whirling motion of the molten contents of the crucible have a corrosive effect upon the crucible itself, which reduces the life thereof. The parts of the crucible and of the cover between the passages serve to deflect the gases out of their circular motion and the size of these passages also has a bearing on the extent to which rotary motion of the gases is changed into motion in a generally radial direction. Consequently, for some furnace conditions, a relatively large number of passages may be desirable, while under other conditions, a single passage may be sufficient. The passages between the cover and crucible also have no tendency whatever to deflect the gases of combustion downwardly into the interior of the crucible, and consequently, no heavy particles of material will be thrown out of the gases of combustion into the contents of the crucible, which is very desirable, since foreign materials are apt to have a detrimental effect upon molten metals.

In the use of the furnace described, the cover of the furnace need not be removed unless it is desired to remove the crucible or to obtain access to the interior of the furnace, since the hole or opening in the cover is large enough so that the crucible may be charged and the contents thereof ladled out through the opening in the cover. Because of the particular construction of the passages, which has been described, this large opening in the top of the furnace has no detrimental effect upon the contents of the crucible, since the gases of combustion form a curtain over the crucible, which substantially excludes air from the crucible. Furthermore, by means of the construction shown, the relatively large hole or opening in the cover of the furnace has the advantage that the gases discharged through the passages over the crucible may flow slowly through this large hole, and consequently, remain in proximity to the contents of the crucible for a somewhat longer time, during which they can transmit a larger portion of their heat to the contents of the crucible. Since this heat is transmitted directly to the material in the crucible and does not have to pass through the wall of the crucible, it materially increases the thermal efficiency of the crucible.

Furnaces constructed in accordance with my invention have the further advantages that the crucibles are entirely within the furnaces so that all parts of the crucibles are exposed to substantially the same temperatures, thus avoiding the setting up of strains in the crucibles due to differences in temperature of different parts thereof, as would result in furnaces in which the upper ends of the crucibles extend above the furnaces. By forming the passages for products of combustion in the upper edges of the crucibles or in the covers, manufacture of the crucibles is facilitated and this also gives the crucibles greater effective heights for corresponding overall heights, so that the crucibles have greater capac-

ties for material to be melted than crucibles having passages below their upper portions.

I claim as my invention:

1. A crucible furnace having an outer substantially annular wall, a crucible arranged within said wall to form therewith an annular combustion chamber, a cover for said furnace which closes the upper end of said combustion chamber and which has an opening therein which is substantially coextensive with the open upper end of the crucible, said crucible having a portion thereof of less height measured to the upper edge of the crucible than other portions and spaced from said cover to form a passage for products of combustion from said combustion chamber across the upper portion of said crucible.

2. A crucible furnace having an outer substantially annular wall, a crucible arranged within said wall to form therewith an annular combustion chamber, a cover for said furnace which closes the upper end of said combustion chamber and which has an opening therein which is substantially coextensive with the open upper end of the crucible, said crucible having a notch formed in the upper edge thereof and said cover having a radially extending groove therein and extending from said combustion chamber to said opening in said cover, whereupon products of combustion may pass from said combustion chamber through said notch and said groove in a substantially horizontal direction over said crucible.

3. A crucible furnace having an outer substantially annular wall, a crucible arranged within said wall to form therewith an annular combustion chamber, a cover for said furnace which closes the upper end of said combustion chamber and which has an opening therein which is substantially coextensive with the open upper end of the crucible, said crucible having a notch formed in the upper edge thereof and said cover having a radially extending groove therein and extending from said combustion chamber to said opening in said cover, said groove in said cover being arranged over said notch in said crucible to form therewith a passage through which products of combustion from said combustion chamber flow in a substantially horizontal direction

across the upper portion of said crucible toward the axis thereof.

4. A crucible furnace having an outer substantially annular wall, a crucible arranged within said wall to form therewith an annular combustion chamber, a cover for said furnace which closes the upper end of said combustion chamber and which has an opening therein which is substantially coextensive with the open upper end of the crucible, the upper edge of said crucible being provided at intervals with notches and said cover being provided at intervals with a plurality of grooves formed in the undersurface thereof and extending from the upper portion of said combustion chamber to said opening in said cover, said notches and grooves forming a plurality of substantially horizontal passages between said cover and said crucible for conducting combustion gases from said chamber in a substantially horizontal direction across the upper portion of said crucible, the side walls of said passages acting to guide the products of combustion across the upper portion of said crucible.

5. A crucible for use in a furnace having a cover extending over the furnace and over the upper edge of the crucible, said crucible being provided with a notch in the upper edge thereof of materially greater dimension circumferentially of the crucible than vertically thereof, for forming with the furnace cover a passage through which products of combustion may pass over the top of the crucible in the form of a curtain.

6. A crucible for use in a furnace having a cover extending over the furnace and over the upper edge of the crucible, said crucible being provided with a plurality of notches in the upper edge portion thereof, each of said notches being of materially greater dimension circumferentially of the crucible than vertically, said notches forming with the cover of the crucible a plurality of passages through which products of combustion may flow substantially horizontally across the top of the crucible to form a curtain of products of combustion across the top of the crucible.

CHESTER E. MILLIGAN.
